G. MERLE, SR

CONDENSER

Filed Feb. 5, 1926

INVENTOR
George Merle Sr
BY
Howard C. Thompson
ATTORNEY

UNITED STATES PATENT OFFICE.

GEORGE MERLE, SR., OF BROOKLYN, NEW YORK.

CONDENSER.

Application filed February 5, 1926. Serial No. 86,319.

This invention relates to condensers and, particularly to multi-unit condensers employing a single control for simultaneously operating all of the condenser units; and the object of the invention is to provide a plurality of condenser units of the straight line type mounted in a frame, and means actuated by a single knob or dial for moving the movable plates of each unit into and out of relation with reference to the stator plates of such units; a further object being to provide a multiple condenser of the class described wherein the condenser units are mounted side by side and edge to edge to form a compact structure which will take up the least amount of room; and further, in the provision of a simple and yet sensitive operating means for the movable plates of the condenser units; and with these and other objects in view, the invention consists in a device of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a face view of a part of a panel showing my improved condenser mounted in connection therewith with parts of the construction broken away and in section.

Fig. 2 is a partial section on the line 2-2 of Fig. 1.

The condenser shown for the purpose of illustrating one use of my invention comprises two frame members 5 and 6 composed of any suitable material, preferably hard rubber, bakelite and the like, said frame members being substantially square in form. Adjacent the sides of said frame members and positioned therebetween are four sets of condenser units, each set consisting of stator plates 7, substantially triangular in form, and secured in position by screws or bolts 8 at the corner portions thereof. Movable condenser plates 9 are pivotally mounted to the frame members 5 and 6 as seen at 10, and positioned between said frame members and centrally between and in spaced relation with the stator plates 7.

The movable plates 9 are of less dimensions than the stator plates 7, and are substantially triangular in form in the con-

struction shown, the pivot pins 10 being at one corner portion of the movable plates. A pin 11 is coupled with another corner portion of the movable plates 9 of each unit, and is provided with a forwardly or outwardly directed shank portion 12 on which is mounted a two-part bearing and keeper 13 which operates in an elongated aperture 14 in the arms 15 of a four-arm crank or operating device 16 rotatably mounted on a shaft 17 mounted centrally of the frame member 5. A large gear 18 is mounted on the shaft 17, and meshing with this gear is a pinion 19 mounted on a shaft 20 supported in the frame member 5 and which extends forwardly through the panel 21 of a radio apparatus. Mounted upon the protruding end of the shaft 20 is a knob dial 22, by means of which the pinion 19, gear 18 and crank 16 may be operated for moving the movable plates 9 inwardly and outwardly with relation to the stator plates 17 of the separate condenser units. The condenser is supported in connection with the panel 21 by screws or bolts 23.

It will be noted that the stator plates 7 of the separate condenser units on the adjacent edges thereof when mounted in the frame members 5 and 6 are spaced apart, and partition wall members 24 are mounted in the frame members 5 and 6 in cross relation, and are positioned between the adjacent faces of the stator plates in the separate units, thus dividing the condenser into four compartments, in each of which one of the condenser units, comprising the movable and stator plates, is mounted.

In the operation of my improved condenser, it will be understood that by rotating the dial or knob 22, the gears 19 and 18 will be rotated to impart rotary movement to the crank or operating member 16. From the position of the parts shown in Fig. 1 of the drawing, a movement of the crank will operate to move the plates 9 outwardly with reference to the stator plates in all of the units. In this operation, the bearings 13 on the reduced ends 12 of the pins 11 will move outwardly in the apertures 14 in the arms 15 as partially indicated in dotted lines in Fig. 1 of the drawing, wherein the movable plates of one of the units is shown extended.

It will be understood that each condenser unit may control a particular circuit or coil of a radio apparatus, or two or more of the

units may be coupled together in any desired manner; and while I have shown certain details of construction for carrying my invention into effect, and including specific form 5 of stator and movable plates, it will be understood that I am not necessarily limited to the specific structures herein shown and described, and various changes therein and modifications thereof may be made within 10 the scope of the appended claims without departing from the spirit of my invention or sacrificing its advantages.

Having fully described my invention, what I claim as new and desire to secure by 15 Letters Patent, is:—

1. A condenser of the class described comprising a plurality of independent condenser units consisting of stator plates and movable plates of each unit, one end of the movable plates being pivoted whereby the same are swung bodily from said pivot into and out of communication with the stator plates of the separate units, and means in operative connection with the free end portions of said 25 movable plates of all the units for operating said plates and for moving the plates of the separate units simultaneously.

2. A condenser of the class described comprising a plurality of condenser units consisting of stator plates and movable plates, one end of the movable plates being pivoted whereby the same are swung bodily from said pivot into and out of communication with the stator plates, means in operative 35 connection with the free end portions of said movable plates for operating said plates and for moving the plates of the separate units simultaneously, said means comprising a rotatable member having a plurality of arms, the free end portions of which are provided with elongated apertures in which pins on said movable plates operate.

3. A condenser of the class described comprising a plurality of condenser units consisting of stator plates and movable plates, one end of the movable plates being pivoted whereby the same are swung bodily from said pivot into and out of communication with the stator plates, means in operative 50 connection with the free end portions of said movable plates for operating said plates and for moving the plates of the separate units simultaneously, said means comprising a rotatable member having a plurality of arms, the free end portions of which are provided with elongated apertures in which pins on said movable plates operate, a gear on the shaft of said rotatable member, and a pinion meshing with said gear, said pinion being rotated by a knob dial for imparting movement to said member and said movable plates.

4. A condenser of the class described comprising two frame members substantially 55 rectangular in form, a plurality of con-

denser units mounted within and between said frame members, each unit consisting of a plurality of stator plates and movable plates, the movable plates being pivoted at one end to said frame members whereby the same may be swung bodily into and out of communication with the stator plates, the free end of said movable plates being coupled together by pins having projecting portions provided with bearings, a member for actuating said movable plates provided with a plurality of arms having elongated apertures at their free ends in which the bearings on the movable plates operate, whereby the operation of said member will move simultaneously the movable plates of all of said units.

5. A condenser of the class described comprising two frame members substantially rectangular in form, a plurality of condenser units mounted within and between said frame members, each unit consisting of a plurality of stator plates and movable plates, the movable plates being pivoted at one end to said frame members whereby the same may be swung bodily into and out of communication with the stator plates, the free end of said movable plates being coupled together by pins having projecting portions provided with bearings, a member for actuating said movable plates provided with a plurality of arms having elongated apertures at their free ends in which the bearings on the movable plates operate, whereby the operation of said member will move simultaneously the movable plates of all of said units, and means for operating said member.

6. A condenser comprising stator plates and movable plates, and means for actuating said movable plates comprising a rotatable member having an elongated aperture, and means on the movable plates mounted in and movable in the aperture of said member whereby the rotation of said member will move said plates toward and from the stator plates.

7. A condenser comprising stator plates and movable plates and means for actuating said movable plates comprising a rotatable member having an elongated aperture, means on the movable plates mounted in and movable in the aperture of said member whereby the rotation of said member will move said plates toward and from the stator plates, and means for operating said member comprising a knob dial gear in connection therewith.

8. A condenser of the class described comprising a plurality of stator plate units arranged in juxtaposition and spaced relation, said units being triangular in form, a plurality of movable plate units mounted for cooperation with said stator plate units, said movable plate units having triangular plates

adapted to operate between the plates of the stator units, and said movable plate units being pivoted at one corner portion thereof and being swung bodily toward and from the stator plate units.

9. A condenser of the class described comprising a plurality of stator plate units arranged in juxtaposition and spaced relation, said units being triangular in form, a plurality of movable plate units mounted for cooperation with said stator plate units, said movable plate units having triangular plates adapted to operate between the plates of the stator units, said movable plate units being pivoted at one corner portion thereof and being swung bodily toward and from the stator plate units, and means for simultaneously operating all of the movable plate units.
10. A condenser of the class described comprising a condenser frame, a plurality of independent condenser units mounted in said frame side by side and in spaced relation, the inner ends of the stator plates of said units being adjacent centrally of said frame, the movable plates of said units being adapted to move into and out of said frame in the operation thereof, an operating member arranged at one side of said condenser units, and with which the movable plates of the separate units are coupled whereby the movable plates of all of the units are simultaneously operated by said member with reference to the stator plates of said units, and means for actuating said member.
11. A condenser of the class described comprising a condenser frame, a plurality of in-

dependent condenser units mounted in said frame side by side and in spaced relation, the inner ends of the stator plates of said units being adjacent centrally of said frame, the movable plates of said units being adapted to move into and out of said frame in the operation thereof, an operating member arranged at one side of said condenser units and with which the movable plates of the separate units are coupled whereby the movable plates of all of the units are simultaneously operated by said member with reference to the stator plates of said units, and means for actuating said member.

12. A condenser of the class described comprising a condenser frame, a plurality of independent condenser units mounted in said frame side by side and in spaced relation, the inner ends of the stator plates of said units being adjacent centrally of said frame, the movable plates of said units being adapted to move into and out of said frame in the operation thereof, an operating member arranged at one side of said condenser units and with which the movable plates of the separate units are coupled whereby the movable plates of all of the units are simultaneously operated by said member with reference to the stator plates of said units, and means for actuating said member, said means comprising gears and a knob.

In testimony that I claim the foregoing as my invention I have signed my name this 1st day of Feb., 1926.

GEORGE MERLE, Sr.
